CLAIM

The ornamental design for an earring, as shown and described.

DESCRIPTION

FIG. 1 is a perspective view of my new earring;

1 Claim, 2 Drawing Sheets

FIG. 2 is a perspective view thereof having the broken line showing of environmental structure removed therefrom;

FIG. 3 is a top plan view thereof;

FIG. 4 is a front elevational view thereof;

FIG. 5 is a bottom plan view thereof;

FIG. 6 is a rear elevational view thereof; and

FIG. 7 is a right side elevational view thereof, the left side being a mirror image thereof;

FIG. 8 is a perspective view of an earring showing a second embodiment of my new earring;

FIG. 9 is a perspective view of FIG. 8.

FIG. 10 is a top plan view of FIG. 8.

FIG. 11 is a front elevational view of FIG. 8.

FIG. 12 is a bottom plan view of FIG. 8.

FIG. 13 is a rear elevational view of FIG. 8; and,

FIG. 14 is a right side elevational view, the left side being a mirror image thereof.

The broken line showing of indicia in FIGS. 1 and 8 and attaching elements in FIGS. 1, 3, 4, 6, 7, 8, 10, 11, 13 and 14 is for illustrative purposes only and forms no part of the claimed design.

FIG. 2**FIG. 1****FIG. 3****FIG. 6****FIG. 4****FIG. 7****FIG. 5**

FIG. 8**FIG. 9****FIG. 10****FIG. 13****FIG. 11****FIG. 14****FIG. 12**
